UNITED STATES PATENT OFFICE.

MICHAEL H. MALONEY, OF CHELSEA, MASSACHUSETTS.

SPINNING-RING

No. 897,384.

Specification of Letters Patent.

Patented Sept. 1, 1908.

Application filed August 29, 1906. Serial No. 332,518.

To all whom it may concern:

Be it known that I, MICHAEL H. MALONEY, of Chelsea, in the county of Suffolk and State of Massachusetts, a citizen of the United States, have invented a new and useful Improvement in Spinning-Rings, of which the following is a full, clear, and exact description, reference being had to the accompanying drawings, forming a part of this specification, in explaining its nature.

My invention relates to an improvement in spinning rings. Spinning rings have been made either stationary or rotary and the rotary rings have been either driven or free to rotate. In the latter case the ring is provided with a traveler, so called, and the ring itself being free to rotate is started and kept in motion by the frictional engagement of the traveler with it, the endeavor having been to so mount the ring that it will rotate as nearly as possible in harmony with the speed of the traveler. With the freely rotating ring, also, not only is the motion of the ring rotary, but as the ring to rotate must have a certain amount of freedom from contact with the flanges or guides which restrain its movement both vertically and radially, the ring must of necessity yield slightly both vertically and radially to the pull of the thread upon the traveler. A thorough trial of such a ring has shown that it is an advance over both the stationary ring and the driven ring, but it has also shown that the attempt to have the ring rotate as nearly as possible in harmony with the speed of the traveler causes difficulties which greatly impair the value of the ring and detract from its commercial value. Nevertheless rapidity of motion and steady speed have always been considered by the votaries of the rotary ring as essential to success in ring spinning in order to secure stronger yarn and to enable the traveler to follow greater speed of spindle than is possible with a stationary ring, thereby making possible an increase in production. I have found, however, that where the ring is thus free to be caused to rotate rapidly by the friction of the traveler, it tends when started to run away from the traveler owing to momentum, and so prevents that evenness of yarn and softness which is desirable. Moreover there is a constant gathering of momentum or acceleration which causes considerable breakage of yarn during the course of spinning. This

breakage is especially noticeable in stopping or starting the frame. When the frame is stopped the movement of each ring continues and draws from the bobbin a certain amount of slack which is taken up with a jerk when the frame is started again, causing the yarn to snap.

I have found that it is a mistake to allow the ring to rotate rapidly or to have such adaptability with respect to its rotation that the ring will gather momentum; that it is only necessary for the ring to yield with a vibratory motion slightly and easily as the varying tension of the yarn may require and to have only such rotary movement as will enable the ring to yield to excessive friction of the traveler due to the strain of the yarn; the ring otherwise remaining quiescent. My invention therefore is intended to overcome the faults of a freely rotating ring and consists in a ring mounted on what may be termed a carrier. The ring is mounted upon the carrier in such manner as to yield easily to the varying tensions of the yarn, but has no adaptability to rotate independently of the carrier. The carrier on the other hand is mounted so as to freely rotate, freely in the sense that it has freedom of rotation but with an adaptability such that it and the ring carried by it will rotate not in harmony with the traveler so as to gather momentum or acceleration, but will rotate or give rotary upon excessive friction of the traveler due to strain upon the yarn. The effect is that the ring will yield with a vibratory motion to the ordinary varying tensions upon the yarn and when a strain comes upon the yarn due to the friction of the traveler or for other reason, then in addition to its vibratory motion above referred to, the ring, or rather the ring and its carrier, will yieldingly rotate and prevent a stretching or snapping of the yarn. In such embodiment of my invention I have found that there is no wildness of movement and that there is a noticeable lack of breakage. There is practically no breakage in starting a frame because when the frame is stopped, the ring having no momentum and moving only intermittently when there is sufficient frictional contact with the traveler, becomes as it were stationary immediately as the power is shut off.

With this construction I have succeeded in obtaining not only a stronger but a softer yarn and have made it possible to do on a

spinning frame, work that heretofore could be done only by mule spinning, and I have been enabled to use large rings in substitution for smaller rings formerly necessary in spinning softer yarn or filling, thereby making it possible to obtain larger bobbins and save time formerly lost in doffing. Moreover with the improved construction it is found that it is possible to increase the speed of the feed 10 roller, thus feeding out more of the roving to be spun into yarn. While this means taking out some of the twist, it does not materially decrease the strength of the yarn, thus I am enabled to produce from ten to twelve per 15 cent. more yarn without additional cost of power and still maintain the strength of any numbered yarn above the scheduled standard of breakage strength of said numbered yarn. Additional increase of product is possible by reason of the adaptability of my device to any speed of spindle. In fact, the production is limited in no way by ring or traveler as in the old stationary ring style of spinning, and the production is therefore limited only by the capacity of the spindle and frame.

Referring to the drawings:—Figure 1 shows a plan of a construction embodying my invention looking down upon the same. 30 Fig. 2 shows a plan of the same construction looking towards the under side of the same. Fig. 3 is a cross section on the line 3—3 of Fig. 1. Fig. 4 is a cross section on the line 4—4 of Fig. 1. Fig. 5 is a cross section on the line 5—5 of Fig. 1.

In the drawings:—A is a ring of the ordinary kind having a lower flange a and an upper flange a^1 on which runs the traveler a^2 . The ring is loosely mounted on what may 40 be termed a carrier B resting on bearings or supports consisting of projections b extending inwardly from the body of the carrier, the ring being loosely mounted in the sense that it has a limited degree of vibratory 45 movement and this preferably in both a lateral and vertical direction with respect to the carrier but with no rotary movement or appreciable rotary movement with respect to the carrier or at least no such movement with 50 respect to the carrier that the ring will gather momentum with respect thereto. It is evident that the ring might be mounted to rotate through less than a complete cycle of movement with respect to the carrier and 55 my invention still be practiced, though in my opinion less effectively. For the purpose of thus mounting and retaining the ring there extends upwardly from the carrier flanges or clips b^1 which loosely embrace the lower 60 flange of the ring, or in other words, loosely enough to permit of the ring having a limited degree of vibratory movement and which vibratory movement, as said before, is preferably both lateral and vertical. As a means 65 for preventing rotation of the ring with re-

spect to the carrier, which means will not interfere with its free vibratory movement, as before described, the ring on the under side thereof is provided with a dependent lug a^3 which fits into a recess or slot b^2 formed in 70 one of the bearings b (see Fig. 4), on which the ring is resting.

The carrier B is preferably annular in shape or of such shape as will permit of its having a complete rotary movement. It is 75 supported by a base C. To this base are attached slotted supports c in the slots c^1 of which the edges of the carrier are contained with the carrier resting upon the supports. The slots c^1 in the support c are so made that 80 the carrier will fit loosely within them so that the carrier will be capable of free rotation. Consequently by reason of this very freedom of rotation it will have a limited degree of vibratory or vertical and lateral movement. 85 The carrier B is placed in position with its edges contained within the slots c^1 of the support c when the device is assembled, by making one of the supports c attachable to the base after the carrier has been placed in 90 proper position to rest upon and be retained by the other supports. Such attachment of the support may be made by fastening it to the base by means of a screw or other detachable fastening c^2 which fastens through 95 the base into the support. With such a construction the ring loosely mounted as it is, will yield with a vibratory movement to any slight pull upon the yarn. Such movement is sufficient to overcome ordinary strains. 100 In case of more severe strains, however, then the ring will freely rotate, or the ring and carrier together, until such strain is relieved. Practically the carrier acts as a drag upon 105 the ring enabling it to vibrate but preventing its rotation upon a light strain and providing a means of rotation to overcome heavier ones.

It is to be understood, of course, that various forms of construction may be employed 110 and still embody the spirit of my invention; any form or style of base or setting may be used; even the frame itself may be used for the rest or support for the carrier.

Having thus fully described my invention, 115 I claim and desire to secure by Letters Patent of the United States:—

1. A device of the character specified having a traveler ring, a rotatable carrier upon which said ring is loosely mounted, and 120 means whereby in the operation of the device said carrier by its weight will act as a rotatable drag against the free rotation of said ring.

2. A device of the character specified having a traveler ring, a rotatable carrier, means for loosely mounting said ring upon said carrier to have a vibratory motion with respect thereto, and means connecting said traveler ring and carrier whereby in the operation of 125 130

said device said ring and carrier will rotate together.

3. A device of the character specified having a traveler ring, a carrier for said ring, 5 means for loosely mounting said ring upon the carrier, said ring being adapted to yield with a vibratory movement to said carrier upon the application of light pulls to said ring in the operation of the device, means 10 connecting said ring with said carrier whereby said ring will rotate with said carrier, and means for mounting said carrier to be freely rotatable.

4. An article of the character specified 15 having in combination a traveler ring, a carrier therefor, means for loosely mounting said ring upon said carrier whereby said ring will have a relative movement with respect to said carrier and said carrier rotate in unison therewith as said traveler ring is turned, and means for mounting said carrier to be 20 freely rotatable.

5. A device of the character specified having in combination a traveler ring, a carrier 25 therefor, means for loosely mounting said ring upon said carrier to have relative movement with respect thereto, means whereby said carrier will rotate in unison with said traveler ring as said traveler ring is turned in

the operation of the device, and means for 30 mounting said carrier to be freely rotatable.

6. A device of the character specified having in combination a traveler ring, a carrier therefor, a mounting in which said carrier is freely rotatable; and means whereby in the 35 operation of the device said ring will yield with a vibratory motion with respect to said carrier or said carrier be rotated in unison with said ring.

7. An article of the character specified 40 having in combination a ring, a rotatable carrier, a base or support for said carrier, and means for loosely mounting said ring upon said carrier to yield relatively thereto or rotate in unison therewith depending upon the 45 strain upon said ring.

8: An article of the character specified having in combination a ring, a rotatable carrier for said ring, means for loosely mounting said ring upon said carrier to yield relatively to said carrier when subjected to light strains or be rotatably carried by said carrier when subjected to heavier strains. 50
